UNITED STATES PATENT OFFICE.

ELEANORA PRESCOTT CARREL, OF ELIZABETH, NEW JERSEY.

FIGURE ORACLE.

Application filed August 18, 1926. Serial No. 129,995.

This invention relates to figure oracles and has particular reference to such a device which may be used, for example, to give affirmative or negative responses to inquiries in an arbitrary manner.

An important object of the invention is to provide a figure oracle having a movable member which, after movement, comes to rest in either one of two definite positions 10 as dictated by chance.

Another object is to provide such a device which will be simple in construction, of neat appearance, and which will furnish amusement for children and adults.

Another object is to provide such a device in the form of a human figure with a movable head, the head having a pair of readily distinguishable faces on its opposite sides, and the character of the oracle's response 20 being determined by the position in which the head comes to rest after being moved.

Other objects and advantages will be readily apparent from the following description when taken in connection with the accompanying drawings wherein a preferred embodiment of the invention is shown by way of illustration, and wherein—

Figure 1 is a front elevation of a figure oracle with the head member supported in 30 a position of rest;

Figure 2 is a side elevation of the same;

Figure 3 is a fragmentary top plan view of the body portion, with the head member shown in section;

Figure 4 is a view illustrating the use of the device with the head member lowered into the body portion;

Figure 5 is a fragmentary view similar to Figure 2 but showing the second face 40 foremost;

Figure 6 is a fragmentary vertical longitudinal sectional view through the body portion; and

Figure 7 is a fragmentary vertical transverse view therethrough.

Referring now to the drawings in detail, it will be seen that the invention contemplates the provision of a relatively stationary support or body 10 and a movable double-faced member 11 normally mounted thereon, said double-faced member 11 being disengageable from the support 10 and rotatable while disengaged. The opposite faces of the member 11 are readily distinguishable from one another to express different meanings, and either one of said faces

may be definitely positioned when the member 11 is restored to engagement with the support 10.

In the specific embodiment shown by way of illustration, the stationary support 10 is in the form of a human figure which may be in a kneeling posture or otherwise as desired. Said figure may be suitably formed as by modelling, molding, carving, or fabricating with any desired material, and may preferably be provided with simulations of dress such as a kimona, or the like. The human figure 10 may be disposed upon a base or pedestal 12 in order that the complete device may firmly rest upon a table, shelf, or the like, and said pedestal having surfaces which may be inscribed with legends desirable in the commercial exploitation of the invention.

The body portion 10 may preferably have a hollow interior 13 and provided at its upper end with an open neck portion 14, the opening in which is slightly larger than the double-faced member 11. Extending downwardly in the neck portion 14 and into the hollow interior 13 are a pair of oppositely disposed grooves 15 and 16 which constitute guiding means as will hereafter be explained, and disposed at opposite sides of each groove 15 and 16, adjacent their upper extremities are a pair of supporting seats 17 and 18 for the normal support of the member 11.

The double-faced member 11 may preferably be in the form of a human head when viewed from the front, and having on one side a face 19 in which the features are of a pleasing appearance, such as embodying a smile, while on its opposite side is a face 20 readily distinguishable from the face 19 as by scowling features. A depending portion 21 may extend downwardly in the open neck portion 14 and may be provided with laterally projecting pins 22 adapted to register with the grooves 15 and 16, or to rest in the supporting seats 17 or 18 as desired. When resting in said supporting seats 17 or 18, the pins 22 are in effect trunnions by which the head member is rockably supported in its normal position. In order that said head member 11 may oscillate on the trunnions a counterbalance weight 23 may be carried by the depending portion 21, such oscillation rendering the device more interesting, and being illustrated by dotted lines in Figure 2.

Means are provided for disconnecting the head member 11 from the stationary support of the body 10, and for freely rotating the head when so disconnected, such means being shown in the form of a cue 24 which may be formed of hair and secured to the head in any suitable manner. A cue is especially appropriate for the oracle when the facial features and dress are those of a Chinaman, but these are details to which the invention is not restricted.

The figure oracle above described will provide amusement and at the same time be ornamental to the home or other environment in which it is used. Frequently people have questions which they must decide and which they find impossible to decide in their own minds. Following a sporting instinct they then flip a coin and settle their doubts in accordance with the chance showing of the coin. The present invention may be used for the same purpose, it giving affirmative or negative responses in an arbitrary manner. Or it may be used by a group of people such as in house parties and the like, the people asking questions by way of entertainment and receiving answers to the questions as will be obvious.

In using the device, the extremity of the cue 24 is grasped between thumb and finger of a person's hand, and extended upwardly to suspend the head member 11 and disengage the pins 22 from the supporting seats 17, 18. It is then moved to bring the pins 22 into registration with the grooves 15 and 16, and then by proper movement of the hand the head 11 is passed downwardly through the open neck portion 14 to a position of free suspension within the hollow interior of the body 10, (see Fig. 4). The desired question is then asked and by manipulation of the fingers the cue 24 is twisted causing the head member 11 to spin freely within the body portion. Thereafter the suspended head and cue are withdrawn upwardly, the pins 22 preferably being forced into registration before the head stops revolving. In this manner it is entirely a matter of chance as to which of the faces 19 or 20 is presented foremost when the head is withdrawn, and since said faces are readily distinguishable from each other, one of them can be held to signify "Yes" while the other signifies "No". The foremost face thus gives the answer or response to the question asked, and in some instances amusing results may be obtained.

From the foregoing it will be evident that a new and novel device has been produced which will have utility for purposes of entertainment and which when properly embellished will be of ornamental appearance. Obviously changes may be resorted to in the details of construction and arrangement of parts, and the right is herein reserved to

make such changes as fall within the scope of the appended claims without departing from the spirit of the invention.

Having thus described my invention, what I claim is:

1. A device of the class described comprising a hollow body which is open at its upper end, a double-faced member adapted to be supported at said upper end and having its opposite faces differentiated from each other to respectively represent affirmative and negative responses, means for lowering said double-faced member into the hollow body and revolving it therein, and means for guiding said double-faced member with either one of its faces foremost as it is withdrawn upwardly from within the hollow body. 75

2. A device of the class described comprising a hollow body in the form of a human figure with an open neck, a head member adapted to be supported thereby and to extend above said open neck, said head member having a pair of faces on its opposite sides and said faces being readily distinguishable from one another to express different meanings, means for lowering the head member through said open neck to a position within the hollow body and for freely rotating the head therein and means for guiding the head upwardly when withdrawn whereby either one of the faces will be foremost as chance directs after rotation. 90

3. A device of the class described comprising a hollow body in the form of a human figure with an open neck, said neck having vertical guiding means, a head member adapted to be supported thereby and to extend above said open neck, said head member having a pair of faces on its opposite sides, and said faces being readily distinguishable from one another to express different meanings, said head member having means for engaging said guiding means whereby to present either of the faces foremost, and means for lowering and raising the head member into and out of the hollow body and for freely rotating it when within the body, the guiding means being disengaged when the head member is lowered. 105

4. A device of the class described comprising a hollow body in the form of a human figure with an open neck, said neck having vertical guiding means, a head member adapted to be supported thereby and to extend above said open neck, said head member having a pair of faces on its opposite sides and said faces being readily distinguishable from one another to express different meanings, said head member having means for engaging said guiding means whereby to present either of the faces foremost, and a cue secured to the head member for lowering and raising the head member into and out of the hollow body and for freely rotat- 125

ing it when within the body, the guiding means being disengaged when the head member is lowered.

5. A device of the class described comprising a hollow body in the form of a human figure with an open neck portion having a pair of vertical grooves and head-supporting seats adjacent its upper end, a head member movable into and out of said hollow body, said head member having a pair of faces on its opposite sides, and said faces being readily distinguishable from one another to express different meanings, pins extending laterally from the head member and adapted 10 for registration in the vertical grooves or to rest upon the head-supporting seats, to rockably support the head member, a counterbalance weight depending from the head member, and a cue secured to the head member for lowering and raising it into and out of the hollow body, and for freely rotating it when within the body.

15 6. A device of the class described comprising a hollow body in the form of a human figure with an open neck portion, said neck 20 being below the confines of said vertical grooves when the head is lowered.

25

portion having a pair of vertical grooves and head-supporting seats adjacent its upper end, a head member movable into and out of said hollow body, said head member having a pair of faces on its opposite sides, and said faces being readily distinguishable from one another to express different meanings, pins extending laterally from the head member and adapted for registration in the vertical 30 grooves or to rest upon the head-supporting seats, to rockably support the head member, a counterbalance weight depending from the head member, and a cue secured to the head member for lowering and raising it into and out of the hollow body, and for freely rotating 35 it when within the body.

7. A device of the class described comprising a support, a multi-faced member rockably supported thereon and having its separate faces readily distinguishable from one another by different expressions, and means for disengaging the multi-faced member 40 from the support and for revolving it while disengaged.

ELEANORA PRESCOTT CARREL.
